UNITED STATES PATENT OFFICE.

OTTO HILDEBERT MUELLER, OF BERLIN, GERMANY.

CONDENSER.

SPECIFICATION forming part of Letters Patent No. 758,090, dated April 26, 1904.

Application filed May 16, 1903. Serial No. 157,382. (No model.)

To all whom it may concern:

Be it known that I, OTTO HILDEBERT MUELLER, engineer, a subject of the German Emperor, residing at 27 Rankestrasse, Berlin, W., in the German Empire, have invented certain new and useful Improvements in or Connected with Jet-Condensers, of which the following is a specification, reference being had to the drawing hereunto annexed, and to the letters marked thereon—that is to say:

This invention has for its object to obtain the best vacuum with a limited quantity of cooling-water in jet-condensers and also to reduce to a minimum the changes in intensity of the vacuum arising from unequal admission of the exhaust-steam to the condenser system.

In order to obtain the above results, I provide two or more jet-condensers of any suitable type arranged in series in such a way that the cooling-water entering one of the condensers, where it is distributed in any of the usual ways, will not be allowed to flow off or be pumped out to the atmosphere, but will be collected in the lower part of said condenser and afterward passed into the next condenser of the series by means of pumps or flow thereinto by gravity, be again distributed and collected, and afterward introduced into the third condenser, if such exist, and so on until after having passed the last condenser in the system it will be allowed to flow off or be pumped out to the atmosphere, while the exhaust-steam is conducted in the opposite direction through the condensers and the vacuum-pump is connected with that condenser into which the water first enters and the exhaust-steam terminates its passage through the system.

The invention will be clearly understood from the accompanying drawing, which represents diagrammatically a vertical section of two condensers connected in the way described; but although two only are shown it will be understood that the number of condensers may be increased, if desired.

In the drawing, *a* represents a jet-condenser of the barometer type with tail-pipe *c*, and *b* represents a second jet-condenser. Water is admitted by a pipe *d* into the condenser *b*,

where it is sprayed, and it is then conducted by a pipe *e* into the condenser *a*, where it is again sprayed. The cooling-water therefore passes through the condensers in the direction indicated by the arrows marked 1 to 7, 55 while the exhaust-steam is admitted at *f* to the condenser *a*, whence it passes through the pipe *g* into the condenser *b* below the water-spray, following the direction of the arrows 8 to 10, and the air separated during the 60 process of condensation is drawn off at the pipe *h* in the direction of the arrow 11 by means of a vacuum-pump *i* of any suitable kind.

It will be readily understood that the exhaust-steam being first exposed to a spray of warm injection-water and afterward to another spray of cold water will be efficiently condensed and separated from the air mixed with it, the latter following the way of the 70 vapors from *a* to *b*, and finally being drawn off in a concentrated and cold state at *h*. It will also be seen that during periods when little steam enters the condenser *a* the condensation will in great part be completed in *a*, while 75 the coolness of the water in *b* will increase. If, however, either gradually or suddenly a heavier load of exhaust-steam be thrown upon the system, the condenser *b* will take a greater share in the condensing action until the volume 80 of exhaust-steam admitted is again reduced. Under these conditions the condenser *b* may for the time being do the whole work of condensation, as meanwhile much warmer water 85 than before will have accumulated at the bottom thereof and enter the condenser *a*, through which it flows without performing any condensing action until after a time the water accumulating in *b* and passing to *a* becomes 90 cooler again and the original state of the condensing process is re-established.

The condenser *b* should preferably have a sufficient storage capacity to allow for the periods of heavy steam load, which latter being known the former is a simple matter of calculation.

The arrangement of parts hereinbefore set forth is very convenient when local conditions are to be met or existing single condensing plants extended or combined with a view of 100

obtaining improved efficiency or larger capacity.

Having now particularly described and ascertained the nature of the said invention and in what manner the same is to be performed, I declare that I do not claim to have invented a new method of condensing steam, it being known that the steam can be conducted in a direction opposite to that of the condensing-water with advantage and also that pockets arranged within a condenser or attached to it from the outside and subsequently filled by the injection-water have the effect of equalizing the vacuum under varying admission of steam; but

What I do claim as my invention is—

1. In a condensing apparatus, the combination of a plurality of jet-condensers, the first having a steam-inlet opening, and a steam-outlet opening, and the second having a steam-inlet opening connected with the steam-outlet opening of the first, a jet device for connection with a cold-water supply and adapted to deliver a jet into the second condenser, and a jet device connected with the lower part of said second condenser, and adapted to deliver a jet into the first condenser, said condensers being otherwise unconnected, whereby the water passes through said condensers but once.
2. In a condensing apparatus, the combination of a plurality of jet-condensers, the first having a steam-inlet opening, and a steam-outlet opening, and the second having a steam-inlet opening connected with the steam-outlet

opening of the first, a jet device for connection with a cold-water supply, and adapted to deliver a jet into the second condenser, a jet device connected with the lower part of said second condenser, and adapted to deliver a jet into the first condenser, said condensers being otherwise unconnected, whereby the water passes through said condensers but once, and an air-pump connected with said second condenser.

3. In a condensing apparatus, the combination of a plurality of jet-condensers arranged in series, each having a steam-inlet opening, and each having a water-inlet at its upper part and a water-outlet at its lower part, an air-pump connected to the last condenser, a jet device for each condenser adapted to discharge into same above its steam-inlet, a connecting steam-passage between each two condensers leading from the body of the one to the steam-inlet of the other, and a connecting water-passage between each two condensers leading from the water-outlet of the one to the water-inlet of the other, said condensers being unconnected except by such two passages, whereby the condensing-water is used but once.

In witness whereof I have hereunto signed my name in the presence of two subscribing witnesses.

— OTTO HILDEBERT MUELLER.
